DESIGN FOR A DRESS

Pauline Wood, New York, N. Y.

Application September 7, 1937, Serial No. 71,496

Term of patent 3½ years

To all whom it may concern:

Be it known that I, Pauline Wood, a citizen of the United States of America, residing in city of New York, county of New York, and State of New York, have invented a new, original, and ornamental Design for a Dress, of which the following is a specification, reference being had to the accompanying drawing, forming part thereof.

Fig. 1 is a front view of a dress showing my new design.

Fig. 2 is a rear view thereof.

Fig. 3 is a side view of the sleeve showing the cuff portion turned up.

The characteristic feature of my design resides in the combination on the dress disclosed of the inverted T shaped stitched design, on the waist portion of the dress as shown in association with the specific stitching on the bottom portion of the sleeve as shown.

I claim:

The ornamental design for a dress substantially as shown and described.

PAULINE WOOD.
